DROP STAFF BRAKE MECHANISM

Jack Wilson, Chicago, Ill., assignor to Universal Railway Devices Company, a corporation of Delaware

Application July 17, 1942, Serial No. 451,251

2 Claims. (Cl. 74—510)

This invention relates to brakes for railway cars, and more particularly for use on flat cars and the like.

The principal object of the invention is the provision of a new and improved brake operating mechanism having a drop staff, together with new and improved mechanism for so mounting the shaft that when it is in elevated position it will extend to a maximum height in order that it may be easily accessible when it is desired to use the same.

Another object of the invention is the provision of new and improved brake operating mechanism so constructed that the brake operating chain or cable will not foul the truck wheel while the car is rounding curves.

A still further object of the invention is the provision of a new and improved drop staff brake operating mechanism having a novel arrangement of the means for supporting the staff in its elevated position.

A further object of the invention is the provision of a new and improved drop staff brake operating mechanism that is simple in construction, powerful in operation, comparatively inexpensive to manufacture and install, that is efficient in operation, and that is rugged in construction and easy of operation.

Other and further objects and advantages of the invention will appear from the following description taken in connection with the accompanying drawings, in which

Fig. 1 is a top plan view of a flat car showing the invention applied thereon, with parts broken away;

Fig. 2 is a longitudinal section through the line 2—2 of Fig. 1, with parts broken away;

Fig. 3 is a section through the line 3—3 of Fig. 2, with parts broken away and showing the car wheel in the position it assumes in rounding curves of comparatively short radii;

Fig. 4 is a section on the line 4—4 of Fig. 2;

Fig. 5 is an end elevation of a portion of the car with the invention in position thereon and with parts broken away;

Fig. 6 is a vertical section similar to Fig. 4 but on a smaller scale, showing a modified form of the staff supporting member or stirrup; and

Fig. 7 is a similar view of a further modified form of construction, with parts broken away.

It is common practice to provide flat cars with drop brake staffs so that, if desired, the staff may be lowered beneath the floor level in order to provide clearance for certain types of lading. It is desirable that when the brake staff is in its

uppermost position it be at a maximum height for convenience in operation. The present traffic rules require that the staff shall be a predetermined distance above the rails when in lowered position. In the brake installations as practiced at the present time the staff is necessarily comparatively short, due to the manner in which they are installed and supported.

The present invention seeks to remedy this difficulty by providing a new and improved design for the supporting mechanism for the brake staff. One manner of accomplishing this result is disclosed in the present system, wherein the gear mechanism is so constructed and so mounted that only the brake drum gear will be below the end sill, while the remaining gear mechanism will be located at the end of the car above the horizontal plane of the lower portion of the end sill.

Another plan is to mount the supporting stirrup in such manner that it will hold the staff in its highest position. By providing a recess in the lower end of the brake staff pinion into which the pin in the lower end of the staff may be drawn, additional length may be added to the brake staff, as will presently appear.

Furthermore, by combining all of these arrangements the staff may be made much longer than would otherwise be possible.

All of this is considered an important feature of the invention, because it permits the staff to be elevated to its highest possible position where it is much more convenient for the brakeman in applying the brakes.

Referring now to the drawings, the reference character 10 designates a railway flat car showing the invention in position thereon. The car is of the usual or any well known construction, and comprises end sills 12 (Fig. 2), center sill 13, and the floor 14. The car body is adapted to be supported at each end by a truck, one wheel of which is indicated at 15 in Figs. 2 and 3. Since the truck is of the usual or any well known construction, it is not thought necessary to further illustrate or describe the same.

The truck is provided with the usual brake mechanism including the brake lever 20 and the draw chain or cable 16, as shown more clearly in Figs. 2 and 3 of the drawings. In the form of construction shown, which is by way of example only, the casing or housing for the brake operating gears has a portion of it extending beneath the car end, as will now be described. Attached to the end sill 12, and extending be-

neath the same, is the casing 17 for containing the brake operating gears.

The casing is rigidly secured to the bottom flange and to the web portion of the end sill 12 by any suitable means, such as the rivets 18, 19, respectively (Fig. 2). This housing comprises a lower portion 21 which extends beneath the flange of the end sill 12, and an upper portion 22 that extends upwardly along the outer face of the end sill. Journalled within the lower or horizontal portion 21 of the casing is a gear 23, having a winding drum 24 thereon, as by being integral therewith, which is of the usual or any well known construction, and to which the outer end of the brake chain or cable 16 is attached. The gear 23 is mounted so that it is in close proximity to the bottom portion of the end sill, and thus the remaining portion of the mechanism will be as far above the tracks or rails as possible so that a longer staff may be employed, as will presently appear.

In order to have access to the rivet 18 for securing the housing in position, the lower section 21 of the housing 17 that extends beneath the end of the car is provided with one or more enlarged openings 25, and the gear 23 is provided with a plurality of openings 26 any one of which may be brought into register with one of the openings 25 so as to have access to the rivets 19 when it is desired to secure the same in position. In order to provide sufficient clearance for the heads of the rivets 18, and at the same time secure the gear 23 in close proximity to the underside of the end sill, the gear 23 has its central portion depressed or recessed, as shown in Fig. 3.

Suitable means are provided for rotating the gear 23, and with it the drum 24, for operating the brakes by winding up the chain or cable 16. A brake staff 28, which is rectangular in cross-section, is employed for operating the brakes. This shaft extends through an enlarged opening 29 in the upper portion 22 of the housing 17, and through an aligned opening 32 in the lower portion thereof. These openings constitute bearings for the upper and lower ends of a pinion 33. This pinion is provided with an upper flange 34 extending over the opening or bearing 29, and a flange 35 which extends over the bearing 32 for limiting the downward movement of the pinion 33. The opening 29 is enlarged to such an extent that, when the bearing is removed, the pinion 33 may be lowered therethrough so that its lower journal 30 may engage the bearing 32, as shown in Fig. 4.

The pinion 33 is provided with an angular axial opening through which is slidably mounted the brake shaft 36. The pinion 33 has its lower end recessed about the shaft 36, as at 37, for receiving a pin 38 which extends through the lower end of the shaft for limiting the upper movement of the latter. By providing the recess 37 the shaft may be elevated a greater distance than would otherwise be possible.

Suitable means are provided for holding the shaft in its upper or operative position. As shown in Figs. 4 and 5, a stirrup 39 is provided for this purpose. The stirrup has upwardly extending arms 41, 42 (Fig. 5), each of which is pivoted between two pairs of lugs 43, 44, integral with the upper portion of the casing 17 at its extreme upper end above the pinion 33, as shown more clearly in Figs. 2 and 5 of the drawings. The upper portion of the arms 41, 42, extend inwardly, and the inwardly extending portions are provided with aligned openings 45, each of which

has an extension or notch 46, indicated in dotted lines in Fig. 4. These notches extend vertically from the openings 45 when the stirrup is in lowered position.

The pivot pins 47, 48, for the arms 41, 42, are rectangular in cross-section, and are held from turning by rectangular openings in the lugs 43, 44, through which they pass. The greatest dimension of these pins is slightly less than the diameter of the openings 45, and the extensions or notches 46 of the openings are so constructed and arranged that when the stirrup 39 is in its inoperative position, shown in Fig. 4, the pivot pins 47, 48, will not engage in the extensions or notches 46. However, these extensions or notches are of such width that when they are vertical the pivots will enter these recesses and lock the stirrup in its lowered position for supporting the shaft in elevated position, as will presently appear.

The lower ends of the arms have a curved connecting member or portion 49, that is, a member that is transversely concave on its upper surface, which is adapted to engage beneath the brake staff when the same is elevated. The arms are just long enough to permit the member 49 to clear the gear-supporting bracket, which may be rounded, as at 50, for this purpose. The stirrup will be moved by gravity from the position shown in Fig. 4, when the lower end of the shaft is raised above the member 49, so that this member will be directly beneath the shaft for supporting the same. This will hold the shaft in its uppermost position, and the pins 47, 48, will enter the notches 46 due to the fact that gravity will lower the entire stirrup when the notches 46 are turned into alignment with the angular pins 47, 48, thereby preventing the movement of the stirrup 49 from beneath the shaft. When it is desired to lower the brake staff the stirrup 39 is raised to disengage the pivot pins 47, 48, from the extensions or recesses 46, and then turned to the position shown in Fig. 4, after which the shaft may be lowered, as shown in dotted lines in Fig. 2.

It will be noted that the pivot pins 47, 48, are mounted on the uppermost portion of the housing 17, whereby the connecting or staff-supporting member 49 of the stirrup 39 will be supported in proximity to the plane of the lower surface of the end sill. As a result of this arrangement the staff may be elevated to a greater height than when the stirrup is hinged at a lower level.

In order that the brake wheel 51, when the staff is lowered, shall be below the upper surface of the floor 14, the floor is provided with a curved recess 52 (Fig. 1), within which the wheel 51 is lowered, as indicated more clearly in dotted lines in Fig. 2. The curvature of this recess is such as to provide the necessary clearance around the wheel. The brake shaft is adapted to rotate the pinion 33, and an idler or intermediate gear 53 is interposed between the pinion and the gear 23. This intermediate gear member is of the power multiplying type, and in order that the brake shaft may be raised to its maximum height the gear train between the brake shaft and the brake drum is such that the intermediate or idler gear 53 is above the plane of the winding drum gear 23. In the form of construction shown the pinion 33 engages the idler gear 53, and this gear has integral therewith, and below the same, a pinion 54 which in turn intermeshes with the gear 23.

It will thus be seen that by means of this arrangement the pinion 33 is in a higher plane

than the gear 23, and consequently the shaft 36 may be raised so that the pins 38 will be above the plane of the gear 23. This is considered one important feature of the invention.

By employing the idler gear and pinion 53, 54, the winding drum 24 will be caused to rotate in the same direction in which the shaft 28 is rotated. Since the drum will be rotated in the same direction in which the shaft is rotated, that is, right-handed, it will be seen from an inspection of Fig. 3 that the brake chain or brake cable will be positioned much farther to the right of the wheel 15 than it would be were the idler omitted, because by omitting the idler the gear 23 must rotate in the opposite direction from that of the shaft, and consequently the brake chain or cable would be on the side of the drum adjacent to the car wheel when the brakes are applied. With the present construction there is no danger of the brake chain fouling the wheel during the operation of the brake, even on rounding curves.

Suitable means are provided for holding the brake in adjusted position. In the form of construction shown a bracket 55, rigidly attached to the end sill 12 of the car by means of rivets 56, is provided. This bracket is provided with axial openings forming bearings for a sleeve 57, having a square axial opening therethrough for receiving the shaft 28, as is usual in such constructions. The sleeve 57 has rigidly attached thereto a ratchet 58, having ratchet teeth 59 on its under side, as clearly shown in Fig. 2 of the drawings. In order to hold the ratchet in adjusted position a suitable pawl 61, pivoted, as at 62 (Fig. 5), is provided. The inner end of this pawl is curved upwardly and is adapted to engage the teeth 59 and the outer end 63 of which extends outwardly beyond the bracket for providing handle means for manipulating the pawl. In order that the pawl may act automatically a weight member 64 is provided. The weight member is also pivoted on the pivot 62, and, when in the position shown in Fig. 5, it will act on the extended end 63 for causing the tooth-engaging end of the pawl to move upwardly into engagement with the teeth.

In releasing the brake the weight member 64 is first thrown to the opposite side of its pivot for freeing the pawl, after which the brakeman moves the brake wheel slightly in the direction of tightening the brake for releasing the pawl by gravity. The brake wheel may now be released, or may be slowly rotated by the operator in reverse position for releasing the brakes.

It will thus be seen that by employing an intermediate gear in the brake operating mechanism the drum will be turned in the same direction as the shaft, thereby removing the brake chain from the side of the drum adjacent the truck wheel to the side farthest from said wheel, as shown in Fig. 3, thus providing sufficient clearance even on sharp curves. Not only this, but the use and arrangement of the intermediate gear permits the staff-holding mechanism to be elevated above the lower side of the end sill, which, together with the recesses in the brake staff pinion into which the pin on the staff may be elevated, and the elevated mounting for the stirrup, all contribute to permit the brake shaft to be elevated to its maximum height when in use without extending near the tracks when in its lowered position.

In Fig. 6 is shown a modified form of the brake staff supporting mechanism. In this form of

construction the gears 23 and 53, and pinions 33 and 54, are the same, and arranged in the same manner, as has already been described. Likewise the brake staff 36 and the housing or bracket 17^a are substantially the same, except that in the modified form of construction the housing is modified to accommodate the different means employed for holding the brake staff in elevated position. In this form of construction the housing 17^a is provided with a pair of depending ears, lugs or extensions 65, which extend vertically downwardly below the brake staff 36. These ears or extensions are connected together adjacent the lower ends by a pivot member 48^a, which is rectangular in cross-section and is similar to the pin 48 in Fig. 4.

The stirrup or staff supporting member 39^a, which is in the form of an inverted U having the arms 41^a provided with aligned circular openings 66 within which the pin 48^a is adapted to rotate for holding the stirrup-holding member, is provided for holding the staff in elevated position. The openings 66 are provided with upward extensions or notches 67, which are adapted to receive the pivot 48^a when the stirrup is in operative position, as indicated in Fig. 6 of the drawings. In order to bias the stirrup member 39 to position vertically beneath the staff 36 a counterweight 68 is provided. The upper cross member 70 of the stirrup is concave on its upper side for engaging beneath the staff 36 when the latter is in elevated position. When it is desired to lower the staff from the position shown in Fig. 6, the stirrup is elevated to remove the pivot member 48^a from the notch 67, after which the stirrup may be turned to the dotted line position in said figure. By means of the counterweight the stirrup will automatically move to the staff-holding position when the end of the staff is elevated above the stirrup. The casing 17^a is provided with a flange 69, which limits the inward movement of the upper end of the stirrup to staff-holding position.

The form of construction shown in Fig. 7 differs from that shown in Fig. 6 in that instead of providing a counterweight for moving the stirrup into operative position the ears 65^a are extended downwardly and outwardly, and their lower ends are connected together by a pivot 71 which is laterally of the vertical axis of the staff 36, as clearly shown in this figure. In this form of construction the stirrup 39^b is also in the form of an inverted U, with the arms connected together at their upper ends by a cross member 68^b, which is concave on its upper surface for engaging beneath the staff 36, as in the other forms of construction. The casing 17^a is provided with a lug or flange 72 for limiting the inward movement of the stirrup when it is in its operative position.

Since the pivot 71 is laterally of the center of gravity of the stirrup, the latter will be held by gravity in its operative position. The arms of the stirrup are provided with laterally extending lugs 73 that are adapted to engage beneath the ears or extensions 65^a for limiting the turning movement of the stirrup when moved to its inoperative position. The stirrup, when moved to the dotted line position shown in Fig. 7, will have its center of gravity to the left of the pivot pin shown therein, so that when the staff 36 is moved upwardly and the pin 38 engages within the recess 37 the stirrup will be automatically moved by gravity to the full line position shown in Fig. 7. It will thus be seen that in the various struc-

tures described each results in an arrangement permitting an extension of the staff of a drop staff brake. It will also be observed that in the present construction these structures all cooperate to permit the use of a brake staff of maximum height when in elevated position and one that will not extend too near the rails when the same is in lowered position.

While the mechanism has been specifically described, it is understood that this is for the purpose of disclosure only, and that the claims are to be given as broad an interpretation as the art will permit.

This is an improvement on the mechanism disclosed in Patent No. 2,007,706, to P. B. Camp, issued July 9, 1935.

It is thought from the foregoing, taken in connection with the accompanying drawings, that the construction and operation of my device will be apparent to those skilled in the art, and that changes in size, shape, proportion and detail may be made without departing from the spirit and scope of the appended claims.

I claim as my invention:

1. In a brake operating mechanism, a bracket comprising a horizontal and vertical section, a gear journaled in said horizontal section and rotatable about a vertical axis, said gear being closely adjacent to the uppermost part of said horizontal section, a winding drum rotatable with said gear but below the same, a pinion carried by said vertical section and having a depending journal portion provided with an enlarged axial opening only beneath the teeth of said pinion, a brake shaft slidably interlocked in said axial opening for rotating said pinion, an idler gear above said first-named gear meshing with said pinion, an idler pinion meshing with said first-named gear for operating said drum when said shaft is rotated, a pin through the lower end

of said shaft for limiting the upward movement of the latter, said first-named pinion having a recess in its lower end for receiving said pin when the shaft is elevated, stirrup means pivoted above said pinion engaging beneath said staff closely adjacent the lower end of said first-named pinion for holding the staff in elevated position, and a pawl and ratchet for holding said shaft in brake holding position.

10 2. In a brake operating mechanism for a railway car, a bracket having a lower portion adapted to extend beneath a car at the end thereof, an upper portion adapted to extend upwardly along the end of the car, a brake drum, a brake drum gear rotatable with the drum about a vertical axis, said gear being adapted to be in close proximity to the said end sill below the same when in operative position on said car, an operating pinion carried by said upper portion, a brake shaft 15 slidable axially through said pinion for rotating the same, an intermediate gear and pinion engaging said pinion and brake drum gear, respectively, said intermediate gear being above said drum gear, means on the lower end of said staff for limiting the upward movement of the latter, said operating pinion having its lower end provided with an enlarged recess below the teeth of said gear for receiving said means when the staff is elevated, angular pivot pins carried by the uppermost portion of said bracket above said operating pinion, a stirrup having upwardly extending arms provided with circular openings for receiving said pivot pins, said openings having notched extensions for receiving said angular 20 pivot pins for holding said stirrup in operative position, said stirrup movable to a position to engage beneath said staff for holding the same in elevated position with its lower end adjacent said operating pinion.

JACK WILSON.
